Primary Examiner — Garth Rademaker*Assistant Examiner* — Katie Stofko(74) *Attorney, Agent, or Firm* — Greenberg Traurig, LLP(57) **CLAIM**

The ornamental design for a food product, as shown and described.

DESCRIPTION

FIG. 1 is a front right perspective view of a food product showing my new design;

FIG. 2 is a front elevation view of the food product shown in FIG. 1;

FIG. 3 is a rear elevation view of the food product shown in FIG. 1;

FIG. 4 is a right side elevation view of the food product shown in FIG. 1;

FIG. 5 is a left side elevation view of the food product shown in FIG. 1;

FIG. 6 is a top plan view of the food product shown in FIG. 1; and,

FIG. 7 is a bottom plan view of the food product shown in FIG. 1.

The evenly-spaced broken lines in FIGS. 1-7 illustrate portions of the food product that form no part of the claimed design. The dash-dot-dash broken lines in FIGS. 1-3, 6 and 7 illustrate the boundary of the claimed design which forms no part thereof.
